UNITED STATES PATENT OFFICE

2,341,438

PORTABLE PERCUSSIVE TOOL

Clement E. Gossling, Toronto, Ontario, Canada,
assignor to Rogers Majestic Corporation, Dover,
Del., a corporation of Delaware

Application April 16, 1943, Serial No. 483,235
In Canada July 14, 1942

4 Claims. (Cl. 125—33)

My invention relates to percussive tools and more particularly to such tools which while power operated are portable.

From time to time a number of portable tools used for operations requiring percussive and impact motions have been suggested and in fact, marketed. The majority of these were electrically driven and were intended for duties where compressed air was not available. At the present, compressed air driven percussive tools are more suitable for heavier work such as heavy riveting and the like due to the fact that it is not possible to carry in the hand an electric motor of sufficient power for the heavy work intended. There are, however, many applications of a lighter nature, particularly in the building trades for electrically operated portable percussive tools, but the majority of such tools definitely fail to meet all the requirements necessary to achieve full efficiency. To be fully effective they must deal a fast blow which must be obtained with the greatest possible efficiency and the actual striking element must be of the simplest possible geometric form. Oil lubrication of any kind must be eliminated because of the oil retention difficulties in portable apparatus which receives little or no attention. The mechanism must be immune from the effects of bounce on the part of the tool or overfeed of the tool, and should the tool jam on the "in" position, the mechanism must be able to function continuously without stalling the motor. The actual moving mechanism must stay, at all times, in driving contact with the motor so as to positively overcome inertia effects. All the mechanism to operate efficiently and effectively must be of a purely rotary character, and, needless to say, of light weight. The mechanism should, if possible, strike the shank of the tool directly as the interposition of any form of transmitter or socket seriously reduces the value of the blow, as much as 75% of the blow effect being lost if any space is left between the tool shank and the socket.

One of the principal objects contemplated by my invention comprises producing a portable percussive tool which, while simple and rugged in design and construction, achieves effectively all of the above noted desired features.

Another object contemplated by my invention comprises producing a portable percussive tool in which the operating principle is such that accuracy of workmanship in the construction of the tool is not essential.

A still further object contemplated by my invention comprises producing a portable percus-

sive tool of such nature that the tool may be made in sizes varying from those suitable for the lightest type of work to those approaching the limits of portability without material change in the design and operating principle.

I accomplish all of the above noted desirable features and others which will hereinafter become apparent by means of the novel construction, arrangement and interaction of parts which will be hereinafter more specifically described with particular reference to the accompanying drawing forming a part of this specification.

In the drawing which illustrates partially in section and by way of example, one embodiment 15 of my invention, the operating mechanism is enclosed within a housing the portion 1 of which contains the electric motor 5 and is provided with a hand grip 2. A trigger switch 3 is conveniently located near the grip for control of the motor 20 5, and a cover plate 30 secured by screw as shown permits access to the switch for assembly purposes and for connecting the conductor 29 to the switch and motor. The motor shaft 6 is provided with a ball bearing 8 carried by a casting 25 22 which in turn is carried by the other portion 27 of the housing. The motor shaft 6 is further provided with a pinion gear 7. This pinion gear meshes with a spur gear 10 carried on shaft 12, the axis of which is parallel with the axis of shaft 30 6 and which is carried in ball bearings 9 and 11. The spur gear 10 is keyed or fixed in any usual to the shaft 12. The shaft 12 and the bearings therefore are retained in the casting 22 by means of the annular cap 21 and cap screws as 20. The shaft 12 is in form a Z shaft with a portion thereof 13 offset or bent at an angle to the axis of rotation of the shaft 12. This offset portion 13 carries the offset shaft 14 which carries the hammer member 15. The hammer member 15 is 35 mounted on a metal sleeve 16 by means of a rubber sleeve 17 and is held in limited outward position by means of screw 18. The hammer member 15 is free to rotate on the offset shaft 14 and also free to slide thereon being retained in its upper limit position by means of compression spring 28. The tool 23 which may be a rivet setting tool, chisel or drive drill, depending upon the work which it is desired to perform, is carried in a sleeve 25 in the nose of the housing member 50 27, the sleeve being retained in position by means of the nut 26. The tool 23 is provided with a collar 24 to limit its backward motion toward the hammer member 15. Cap screws as 19 serve to join the housing members 1 and 27 clamping 55 therebetween the housing separating member 31,

It will be observed that when the motor 5 rotates the shaft 6, the shaft 12 is rotated to carry the hammer member 15 into the position shown in the dotted lines wherein once per revolution the bevelled edge of the hammer member 15 is brought into sharp percussive contact with the head of tool 23. It will be observed that the hammer member face is bevelled so as to present a surface which, upon impact with the tool 23, is normal to the longitudinal axis of the tool. It will also be observed that as the hammer member 15 is free to revolve and slide on the offset shaft 14, a new face of the hammer member will each time be brought into contact with the tool 23 thereby distributing the wear on the hammer member and providing a long life therefore. It will be observed that this novel design is simple, effective, and rugged, that it permits a fast blow to be struck without any friction effects other than rolling friction, that no transmitter is used, and the tool is struck directly by the hammer, that bounce is not detrimental to the mechanism as the striking member can retreat along the offset shaft 14 against the pressure of springs 28. It will be observed that overfeed of the tool would have the same effect as bounce and, therefore, that the motor would continue to drive the tool merely compressing the spring 28 to and fro in the process.

It will be further observed that grease only need be used for the gearing, that no lubrication of any kind is required for the striking mechanism. It will be further noted that the striking element is of the simplest possible construction and accuracy of workmanship is not at all critical. It is immaterial whether the striking member is a good or a bad fit on its supporting shaft, and that the angle of the offset shaft with respect to shaft 12 is by no means critical and may be chosen within wide ranges to suit the particular work for which the tool is designed. It should also be noted that this simple, effective design can be followed closely without material change in producing tools from the small sizes suitable for light work to the very large sizes approaching the limit of portability.

While I have thus illustrated and described, by way of example, one complete embodiment of my invention, it will be apparent that many changes may be made therein without departure from the intended scope and spirit of the invention. I do not, therefore, desire to limit myself to the foregoing except as may be pointed out in the appended claims in which I claim and desire to secure by United States Letters Patent the following:

1. A portable percussive tool comprising, a housing, a shaft carried by said housing, means carried by said housing for driving said shaft, said shaft having a portion near one extremity thereof bent to extend at an angle of less than 90° with the axis of rotation of said shaft, a pinion carried by said bent portion with the axis of said pinion at 90° to the axis of said bent portion, a hammer member rotatively carried by

said pinion and a tool carried by said housing and so positioned relative to said hammer member as to receive therefrom a blow driving said tool in the direction of its longitudinal axis once during each rotation of said shaft.

2. A portable percussive tool comprising, a housing provided with a hand-grip, a shaft carried by said housing, means within said housing for driving said shaft, said shaft having a portion near one extremity thereof bent to extend at an angle of less than 90° to the axis of rotation of said shaft, a pinion carried by said bent portion with the axis of said pinion at 90° to the axis of said bent portion, a circular hammer member rotatively and slidably mounted on said pinion and a tool carried by said housing and so positioned relative to said hammer member as to receive therefrom a blow driving said tool in the direction of its longitudinal axis once during each rotation of said shaft.

3. A portable percussive tool comprising, a housing provided with a hand-grip, a first shaft carried by said housing, means within said housing for driving said shaft, a second shaft carried by said housing, means whereby said second shaft is driven by said first shaft, said second shaft having a portion near one extremity thereof bent to extend at an angle of less than 90° to the axis of rotation of said second shaft, a pinion carried by said bent portion with the axis of said pinion at 90° to the axis of said bent portion, a hammer member rotatively and slidably mounted on said pinion, a spring carried between said hammer member and said bent portion of said second shaft for taking up the rebound of said hammer member and a tool carried by said housing and so positioned relative to said hammer member as to receive therefrom a blow driving said tool in the direction of its longitudinal axis once during each rotation of said second shaft.

4. A portable percussive tool comprising, a housing provided with a hand-grip, a first shaft carried by said housing, means within said housing for driving said shaft, a second shaft carried by said housing, means whereby said second shaft is driven by said first shaft, said second shaft having a portion near one extremity thereof bent to extend at an angle of less than 90° to the axis of rotation of said second shaft, a pinion carried by said bent portion with the axis of said pinion at 90° to the axis of said bent portion, a circular hammer member rotatively and slidably mounted on said pinion, resilient means between the bent portion of said second shaft and said hammer member, a spring carried between said hammer member and the bent portion of said second shaft for taking up the rebound of said hammer member and a tool carried by said housing and so positioned relative to said hammer member as to receive therefrom a blow driving said tool in the direction of its longitudinal axis once during each rotation of said second shaft.

CLEMENT E. GOSSLING.
